FIG. 3

UNITED STATES PATENT OFFICE

123,246

DESIGN FOR A PLAY SUIT ENSEMBLE

Morris Rubin, Chicago, Ill.

Application February 1, 1940, Serial No. 89,934

Term of patent 3½ years

To all whom it may concern:

Be it known that I, Morris Rubin, a citizen of the United States and a resident of Chicago, in the county of Cook and State of Illinois, have invented a new, original, and ornamental Design for a Play Suit Ensemble, of which the following is a specification, reference being had to the accompanying drawing, forming a part thereof.

In the drawing,

Fig. 1 is a front elevation of a play suit ensemble embodying my new design;

Fig. 2 is a rear elevation thereof;

Fig. 3 is a front elevation thereof with the skirt removed; and

Fig. 4 is a rear elevation of Fig. 3.

The characteristic feature of my design resides in the combination, on the play suit ensemble disclosed, of the specific arrangement of partially stitched pleats on both the play suit and skirt members, in combination with the flared sleeves, the stitch trim on the collar, pocket and belt of the play suit member and on the waistband and bow of the skirt member and the serrated bottom edges of the play suit and skirt members, all as shown.

I claim:

The ornamental design for a play suit ensemble, as shown and described.

MORRIS RUBIN.
